UNITED STATES PATENT OFFICE

HENRY VOSSLER, OF PROVIDENCE, RHODE ISLAND, ASSIGNOR TO IMPERIAL KNIFE COMPANY, INC., A CORPORATION OF RHODE ISLAND

POCKETKNIFE

Application filed October 25, 1930. Serial No. 491,110.

My invention relates to pocket-knives and more particularly to the type wherein a non metallic material is employed in the handle scales.

- 5 The essential objects of my invention are to provide rigid and unyielding areas in the handle halves for sustaining the end rivets which perform the functions of blade pintles, or pass through the spacing block when such
- 10 a block is employed in place of the second blade; to avoid the use of bolsters whose mass involve heavy drilling operations; to guard, shield, and protect the constituent parts of the side members; to minimize the
- 15 quantity of celluloid or other expensive ornamenting material; and to facilitate, simplify, and cheapen the assemblage and interengagement of the constituent parts of the handle.
- 20 To the above ends essentially my invention consists in such parts and in such combinations of parts as fall within the scope of the appended claims.

In the accompanying drawings which form a part of this specification,

Figure 1 is a side elevation of a pocket knife embodying my invention,

Figure 2, a vertical longitudinal section thereof,

30 Figures 3 and 4, sections respectively on lines 3—3 and 4—4 of Figure 1,

Figures 5, 6 and 7, perspective views of a cup member, a compensating plate, and a handle scale respectively, and

35 Figures 8 and 9, like views of the individual pivot retaining plates.

Like reference characters indicate like parts throughout the views.

In the form of my invention herein illustrated my pocket knife consists of a handle represented in a general manner by 10 comprising side members 11 and 12 of identical construction in the present instance so that a

40 description of one of the members will serve for both, and similar reference characters will be employed for the corresponding parts of both members.

Two blades 14 are shown supported between the side members, although it is evident that the number of blades is immaterial,

and that when one blade only is present the usual spacing block replaces the second blade. The tines of the blades engage the ends of any usual or desired back spring 16 provided with an opening 18 for the rivet.

55 The two metal frame pieces or companion plates 20 which form the walls of the blade pocket have integral peripheral flanges 21 which constitute the side walls of a cup member 22 of which the frame pieces 20 constitute the bases, and the flanges 21, the sides. The peripheral contours of the frame pieces are of any convenient form to best accommodate the blades or other implements desired to be mounted in the handle. Near the ends of the 60 cups are perforations 23, and intermediate these, a perforation 24.

65 In each cup a metal compensation plate 25, of substantially the same peripheral contour and area as that of the base, and of any preferred shape in cross section, rests against the latter, and has perforations 27 and 28 registering respectively with the perforations 23 and 24.

70 Resting against an intermediate portion of each plate is a handle piece or scale 30, of celluloid, bone or any other similar non-metallic material, and of any preferred peripheral outline or of any preferred cross sectional shape, with its lateral edges contacting 75 with the flange 21, and provided with an intermediate perforation 31, registering with the perforation 28.

75 Resting against the end portions of each plate 25 are metallic attaching plates 32 and 33 of any preferred transverse or longitudinal sectional contour engaging the flange 21, and having inner edges abutting against the ends of the adjacent handle scale 30. The plates 80 32 and 33 have perforations 36 registering with the perforations 27.

85 After the contents of the cup members have been disposed therein as above described the upper transversely tapering peripheral edges of the flanges 21, which abut against the 90 peripheral edges of all the enclosed parts, are by suitable dies inwardly swaged over the marginal portions of the outer faces of the members 30, 32 and 33 and constitute retaining lips 38 which prevent the ingress of dust 95 100

and retain or assist in retaining the assembled parts.

The spring 16 is secured to each of the sides by a rivet 39 passing through the opening 18 and through the perforation 24 of the frame piece. In this instance this rivet also extends through the perforations 28 and 31 in the members 25 and 30, but this extension is not essential and is preferably absent. The 10 end rivets 41 pass through openings 43 in the tines of the blades 14 and through the perforations 23, 27 and 36 in both side members, so that the ends 45 of the rivets are expanded into firm engagement with the metallic attaching plates 32 and 33.

The omission of bolsters in this structure eliminates the expense of heavy drilling, and the presence of the compensation plate 25 enables the employment of a minimum of material in the handle scale 30, which material is comparatively expensive. The metallic attaching plates 32 and 33 insure firm interengagement of and seats for the blade rivets 41, and a security which would be absent were 25 the rivets to be expanded in a nonmetallic strip. The cup members 22 protect and laterally house the various parts assembled therein, and the bases 20 of the cup members are utilized as frame pieces. The lips 38 30 may assist in securing the members 30, 32 and 33 and make the presence of a rivet in the scales 30 unnecessary.

Without departing from the spirit of my invention other modes of applying the principles thereof may be employed than that explained, change being made in the construction herein disclosed, provided the means stated by any of the following claims or the equivalent of such stated means be employed.

40 I claim:—

1. In a knife-handle, a frame piece, a compensation plate engaging the frame piece, a handle scale engaging the compensation plate, attaching plates supported by the 45 frame piece adjacent the ends of the handle scale, and a peripheral flange upon the frame piece engaging the peripheral edges of the handle scale, and attaching plates.

2. In a knife-handle, a cup member comprising a frame piece, and a lateral peripheral flange upon the frame piece, a compensation plate upon the frame piece, a handle scale upon the plate, attaching plates upon the compensation plate abutting against the ends of 55 the handle scale, and a peripheral inwardly directed lip upon the flange engaging the handle scale and the attaching plates.

3. In a knife-handle, a frame piece, a handle scale supported upon the frame piece 60 and of less length than the frame piece, attaching plates supported by the frame piece adjacent the ends of the handle scale, and a peripheral flange upon the frame piece engaging the scale and the attaching plates.

65 4. In a knife-handle, a frame piece, a

handle scale supported by the frame piece, attaching plates supported by the frame piece adjacent the ends of the handle scale, a peripheral flange upon the frame piece surrounding the scale and the plates, and a lip 70 upon the flange engaging the plates and scale.

5. In a pocket-knife, frame pieces, blades between the frame pieces, handle scales carried by the frame pieces and of less length than the frame pieces, attaching plates adjacent the ends of the scales, peripheral flanges upon the frame pieces engaging the scales and attaching plates, and rivets in the attaching plates engaging the frame pieces and the blades.

75 In testimony whereof I have affixed my signature.

HENRY VOSSLER.
